WAIST ENCIRCLING BELT FOR SUPPORTING
GUITARS AND THE LIKENorman G. Raleigh, 802 Pepper Drive, El Cajon, Calif.
Filed Nov. 20, 1961, Ser. No. 153,614

1 Claim. (Cl. 84—327)

This invention relates to musical instruments, and more particularly to supporting means therefor.

Background

It is well recognized that various instruments, such as guitars, and the like, tend to be too heavy to be comfortably hand-held for long periods. It has therefore become a common practice to support their weight by means of a cord or sling that is looped around the back of the player's neck. This arrangement supports the instrument's weight, and positions the instrument at a comfortable height and orientation for playing it.

A new trend has recently developed in connection with hand-plucked string instruments, this trend being toward the use of electrical pickup to increase volume. This militates against the hollow-bodied instrument, since the sound box is no longer essential. The weight of the instrument is, however, much increased.

The use of steel strings, preferred for their tonal qualities postulates considerable tension placed on the instrument, which must therefore be of strong construction to prevent deformation.

Since the basic shape of the instrument should be retained for psychological reasons, the newer instruments have a heavy, solid, bulky body whose shape approximates the older instruments. This new body introduces a problem for the player, because the neck-looped sling now produces considerable pressure. Moreover, the cord that passes down the front of the player's body is so tight that it pulls the player's clothing, usually his shirt, and produces unsightly wrinkles. In addition, the player must strain to remain erect, when using currently available cords, due in part to the weight of the instrument, and this causes shoulder and back tension.

Objects and Drawings

It is therefore the principal object of my invention to provide an improved instrument support.

It is another object of my invention to provide an improved instrument support that removes the instrument's weight from the player's neck.

It is a further object of my invention to provide an improved instrument support in the form of a belt that permits the instrument's weight to be carried at the waist of the musician.

The attainment of these objects and others will be realized from the following specification, taken in conjunction with the drawings, in which:

FIGURE 1 is a perspective view of the rear of the instrument and the supporting belt; and

FIGURE 2 is a longitudinal sectional view of the belt structure.

Brief Description of the Invention

Broadly speaking, my invention contemplates a half-belt that fits around the back of the musician, and has its ends fastened to the back of the instrument. The belt is thus adapted to remain horizontal, and fits comfortably at the player's waist, while the instrument is properly positioned and angled for the most comfortable playing position.

Detailed Description of the Invention

The invention will be understood from a study of FIGURES 1 and 2 wherein like numerals refer to like or identical parts and portions. An adjustable length half

2

belt 10 has its ends attached to the back portion 12 of the musical instrument 13. As shown, belt 10 is substantially horizontal, and holds the instrument so that the neck portion 14 thereof is at the angle that is most comfortable for the player.

Belt 10 comprises a primary portion 16 that is relatively wide and which may be termed a "half belt." This half belt may be padded if desired, so that it covers a relatively large area of the player's back, and does not cut into the skin. In order to have its length adjustable so that the individual player may adjust it to his own girth and to the snugness that he prefers, a secondary portion or strap 18 is used. This may take any convenient form, the drawings illustrating a strap that has a plurality of aligned apertures at its tongue end 20 so that end may be fastened to the buckle or clasp 22 affixed to the end of the half belt 16. The other end of strap 18 has an easily releasable hook eye 24 or its equivalent, that is secured, as by a loop 26, to the strap 18. Thus, by selecting suitable apertures to engage buckle 22, the overall length of the entire belt 10 can be adjusted to satisfy individual needs.

It will be noted that since the strap 18 does not necessarily engage the back of the wearer, the strap may be of any convenient width without causing cutting or uncomfortable pressure on the wearer's skin.

The other end of the half belt 16, also terminates in a hook member such as the snap hook 28 that is secured to the half belt in any suitable manner.

Each of said hooks is attached to the body 12 of the instrument. One way to do this is to use attachment elements such as screw eyes 30 that are screwed into body portion 12. If desired, the screw eye may have an integral or separate washer 32 to distribute the pressure and strain over a wider area of the body 12 of the instrument and to prevent damage to the finish of the adjacent face of the instrument when the hook eye 24 is being secured and released in use.

Since the musical instrument with which my invention will be used generally has an electrical pickup, the cable 34 therefrom should be supported so that it does not drag or dangle awkwardly as the musician plays and moves around.

I achieve this by means of a supporting link 36 attached to belt 10. Link 36 may be attached in any suitable manner, as for example riveting or sewing, and may be pivotally or fixedly positioned. The cable holding end may also take various forms, such as a ring 38.

In use, screw eyes 30, with or without washers 32, are fastened to the body 12 of the instrument 13 in such a manner that when they are both in a single horizontal plane the neck 14 of the instrument is properly angled and positioned for the player's use. In this way, the player's arms are at a convenient and comfortable location, his shirt is not wrinkled or made unsightly, the weight of the instrument is suspended from the musician's waist and not from his neck or shoulders, and the electric cable is conveniently supported. The wide half belt engages a broad portion of the player's back and is quite comfortable.

Moreover, the adjustable feature of the belt permits the player to achieve the particular degree of snugness that he prefers. This arrangement applies little or no pressure on the player's stomach and no pressure on his chest, which makes it easier for him to join in choral parts, while permitting free movement of the player without dislocation of the instrument from playing position.

While my invention has been described in terms of a solid body musical instrument, it is obvious that it may also be used with hollow body instruments. In those cases, the screw eyes may penetrate the back surface of the hollow body and be fastened at the inside thereof; or

may be bonded to the back of the instrument by suitable adhesives or the like.

It is understood that minor variation from the form of the invention disclosed herein may be made without departure from the spirit and scope of the invention, and that the specification and drawing are to be considered as merely illustrative rather than limiting.

I claim:

The combination comprising:

a guitar having a body portion and a neck portion; 10
spaced attachment elements mounted on the back surface of said body portion, said elements positioned so that when they are in a horizontal plane said neck portion of said instrument is in playing position; an adjustable-length belt having a wide portion and 15
a narrower strap portion;

means positioned at the ends of said belt, for fastening said belt directly to said attachment elements so that when said wide portion is looped around the back of the player, said belt and attachment elements are in said horizontal plane and said neck portion is in playing position and said guitar is thus positioned for maximum comfort of the user, said belt providing the sole supporting means for said guitar.
